US00D848979S

(12) United States Design Patent (10) Patent No.: US D848,979 S
Kim et al. (45) Date of Patent: * May 21, 2019

(54) WIRELESS EARPHONE

- (71) Applicant: LG ELECTRONICS INC., Seoul (KR)
- (72) Inventors: Hyunchul Kim, Seoul (KR); Dongsoon Kim, Seoul (KR); Jinki Min, Seoul (KR); Cheolwoong Shin, Seoul (KR)
- (73) Assignee: LG ELECTRONICS INC., Seoul (KR)
- () Term: 15 Years
- (21) Appl. No.: 35/504,789
- (22) Filed: Oct. 16, 2017

(80) Hague Agreement Data

- Int. Filing Date: Oct. 16, 2017
Int. Reg. No.: DM/098128
Int. Reg. Date: Oct. 16, 2017
Int. Reg. Pub. Date: Apr. 20, 2018

(30) Foreign Application Priority Data

- Sep. 26, 2017 (KR) 30-2017-0045171
- (51) LOC (11) Cl. 14-01
- (52) U.S. Cl. USPC D14/223
- (58) Field of Classification Search
USPC D14/204, 205, 206, 223, 249, 433, 192, D14/172; D24/173, 174, 106; D29/112; D23/223
CPC H04R 25/00; H04R 25/02; H04R 1/10; H04R 2420/07; H04R 2430/01
